UNITED STATES PATENT OFFICE.

SALVATORE GIANGRASSO, OF PORTLAND, MAINE.

FIRE ALARM.

Application filed August 28, 1926. Serial No. 132,234.

This invention relates to certain new and useful improvements in fire alarms and has for its primary object to provide a fire alarm of the audible signal type wherein an electric bell is sounded upon the closing of a switch that is normally retained in an open position by a control device having as a part thereof an inflammable element such as pyroxylin or celluloid, the ignition of which permits 5 the control device to be released for closing the switch and sounding the bell.

A further object of the invention is to provide a fire alarm wherein a single audible signal in the form of an electric bell is in circuit with a source of electric energy and a series of switch devices normally retained in open position by an inflammable fuse which upon being ignited releases the switch for 15 the closing of a circuit and the ringing of the bell, the control device and switch embodying novelty in the assembling thereof.

With the above and other objects in view that will become apparent as the nature of the invention is better understood, the same 20 consists in the novel form, combination and arrangement of parts and in the details of construction hereinafter more fully described, shown in the accompanying drawings and claimed.

30 In the drawings wherein like reference characters are employed to designate corresponding parts throughout the several views,

Figure 1 shows a wall box, partly broken away to show the inclosed battery and bell with electric wires extending therefrom to the switch control device that is illustrated in side elevation as being suspended from a room ceiling;

Figure 2 is a top plan view of the switch 40 control device;

Figure 3 is a bottom plan view of the switch control device;

Figure 4 is a horizontal sectional view taken on line 4-4 of Figure 5;

45 Figure 5 is a longitudinal sectional view of the switch control device showing the spring pressed button switch in its open position and the tensioned plunger for closing the switch held in set position by an inflammable celluloid cap;

Figure 6 is a bottom plan view, similar to Figure 3 with the switch terminals removed from the control device;

50 Figure 7 is a bottom plan view of another form of switch control device;

Figure 8 is a cross sectional view taken on line 8-8 of Figure 7; and

Figure 9 is a diagrammatic view showing the battery, manual switch, bell and a plurality of switch control devices in circuit 60 with the bell and battery.

It being understood that the switch control devices include as a part thereof an inflammable element, said control devices may be positioned at the desired location such as 65 in proximity of the wood work of a room with all of the switch control devices in circuit with a battery and bell, there is illustrated a wall box 1 containing a battery 2 and a bell 3. As shown in Figure 1, a single switch control device 4 is in circuit with the battery 2 and bell 3 by the provision of the wire 5 extending from one pole 6 of the battery to one of the switch contacts 7 while the other wire 8 leads from the other switch 70 contact 9 to the other pole 10 of the battery, it being understood that the bell 3 is interposed in the wire 8 and under control 75 of the manually operable switch 11.

The switch control device 4, any number 80 of which may be provided as diagrammatically illustrated in Figure 9 and interposed in the circuit wires 5 and 8, comprises a base plate 12, preferably of the form illustrated in Figures 2 to 5 that is anchored as at 13 to supporting surfaces 14 that may represent either walls or ceilings, window or door frames or any other part of a building structure, it being noted that the main switch 11 is closed when the fire alarm is in such position while the 90 switch of each control device 4 is open and is adapted to be closed for completing the circuit to sound the bell upon ignition of an inflammable substance, such as celluloid that forms a part of the switch control device. 95

The base plate 12 is provided with an internally threaded opening that receives the enlarged externally threaded annular shoulder 14 of the tubular member 15 that is open 100 at its outer end as shown in Figure 5, the shoulder 14 being enlarged and lying flush with opposite faces of the base plate 12. The end of the shoulder 14 at the wall contacting face of the base plate carries an inwardly directed annular flange 16 that is interrupted for a portion of its length as at 17 while an inwardly directed annular wall 17' is disposed at the opposite end of said shoulder 14.

An insulation strip 18 carries the contacts 110

7 and 9 adjacent opposite ends to which the wires 5 and 8 are respectively attached, the insulation strip 18 being set into the annular shoulder 14 by the provision of the cutaway portion 17 of the flange 16 and being thereafter partially turned has its opposite ends disposed beneath said flange to prevent removal. A push button 19 of the cup-shaped type is set into the annular shoulder 14 as shown in Figure 5 while the spring 20 interposed between the insulation strip 18 and said push button normally separates the latter from the contacts 7 and 9 with the annular flange of the push button engaging the wall 17' to limit separating movement thereof.

The outer end of the tubular member 15 is internally threaded and receives the pipe section 21 while a plunger 22 is reciprocable in the tubular member and pipe section. The inner end of the plunger 22 carries an annular shoulder 23 substantially contacting the inner face of the tubular member while said plunger contacts the inner face of the pipe section 21 to provide for a free reciprocating movement of said plunger. A coil spring 23 incloses the plunger and engages at one of its ends the plunger shoulder 23 while the other end engages the inner end of the pipe section 21. It will therefore be seen from an inspection of Figure 5 that the action of the spring 23 normally supports the plunger in a direction toward the push button 19 for the purpose of closing the switch contacts 7 and 9.

To hold the plunger 22 spaced from the push button 19 against the tension of the spring 23 and also to permit the spring 20 to space the push button from the contacts 7 and 9, there is provided an inflammable device that is associated with the plunger 22, the construction of which is shown more clearly in Figure 5. The outer end of the pipe section 21 receives the cap 24 that is formed of celluloid or other inflammable material, the closed end of the cap 24 having a relatively large opening 25 therein. A stem 26 carried by the plunger 22 extends through the opening 25 and has a nut 27 threaded upon the outer end thereof, the edge of the nut engaging the closed end wall 24^a of the cap 24 outwardly of the opening 25 for holding the plunger 22 partially extended against the tension of the spring 23. When the celluloid cap 24 becomes ignited, the end wall 24^a thereof will burn and the opening 25 being enlarged, the spring 23 removes the plunger 22 for operating the push button 19 to close the switch contacts 7 and 9 for sounding the bell 3.

A plurality of switch control devices are shown in Figure 9, the several push buttons being diagrammatically illustrated by the reference numerals 19^a while the contacts are designated by the reference numerals 7^a and

9^a respectively. With the wire diagram illustrated in Figure 9, it will be observed that when one of the push buttons 19^a is moved into engagement with the adjacent contacts 7^a and 9^a, the circuit will be completed for ringing the bell 3. After the alarm has been given, the circuit may be broken by the main switch 11.

A modified construction of mounting the insulation plate 18 in the base plate 12 is shown in Figures 7 and 8 wherein the flange 16^a of the annular shoulder carries a spring portion 17^a that permits the insulation plate 18 to be snapped into position.

From the above detailed description of the device, it is believed that the construction and operation thereof will at once be apparent, and while there are herein shown and described the preferred embodiments of the present invention it is nevertheless to be understood that minor changes may be made therein without departing from the spirit and scope of the invention as claimed.

What I claim as new is:—

1. A thermally controlled circuit closer comprising a switch and an inflammable device for holding the switch open and adapted when ignited to permit closing of the switch, said switch including an insulation strip, a pair of contacts carried thereby and a terminal push button for the contacts, the inflammable device comprising a tubular member, a reciprocating plunger therein, an annular shoulder on the end of the plunger adjacent the push button, a pipe section threaded into the outer end of the tubular member, a coil spring surrounding the plunger between the shoulder and pipe section, a cap-shaped inflammable element on the outer end of the pipe section, and a pin and nut connection between the plunger and inflammable element for normally holding the plunger inoperative with respect to the push button.

2. A thermally controlled circuit closer comprising a switch and an inflammable device for holding the switch open and adapted when ignited to permit closing of the switch, said switch including an insulation strip, a pair of contacts carried thereby and a terminal push button for the contacts, the inflammable device comprising a tubular member, a reciprocating plunger therein, an annular shoulder on the end of the plunger adjacent the push button, a pipe section threaded into the outer end of the tubular member, a coil spring surrounding the plunger between the shoulder and pipe section, a cap-shaped inflammable element on the outer end of the pipe section, a pin and nut connection between the plunger and inflammable element for normally holding the plunger inoperative with respect to the push button, a base plate mounting for the tubular member, and an interlocking connection

between the tubular member and insulation strip.

3. A thermally controlled circuit closer comprising a switch and an inflammable device for holding the switch open and adapted when ignited to permit closing of the switch, said switch including an insulation strip, a pair of contacts carried thereby and a terminal push button for the contacts, the inflammable device comprising a tubular member, a reciprocating plunger therein, an annular shoulder on the end of the plunger adjacent the push button, a pipe section threaded into the outer end of the tubular member, a coil spring surrounding the

plunger between the shoulder and pipe section, a cap-shaped inflammable element on the outer end of the pipe section, a pin and nut connection between the plunger and inflammable element for normally holding the plunger inoperative with respect to the push button, a base plate mounting for the tubular member, and an interlocking connection between the tubular member and insulation strip, including an annular shoulder on the tubular member having a clearance for one end of the insulation strip. 20 25

In testimony whereof I affix my signature.

SALVATORE GIANGRASSO.
